UNITED STATES PATENT OFFICE.

OVILA J. BENOIT, OF WOONSOCKET, RHODE ISLAND, ASSIGNOR TO SHAMBOW SHUTTLE COMPANY, OF WOONSOCKET, RHODE ISLAND, A CORPORATION OF RHODE ISLAND.

SHUTTLE.

Application filed July 10, 1924. Serial No. 725,150.

To all whom it may concern:

Be it known that I, OVILA J. BENOIT, a citizen of the United States, residing at Woonsocket, in the county of Providence and State of Rhode Island, have invented 5 certain new and useful Improvements in Shuttles; and I do hereby declare the following to be a full, clear, and exact description of the invention, such as will enable 10 others skilled in the art to which it appertains to make and use the same.

The present invention relates to an improvement in shuttles.

The object of the invention is to reorganize and improve shuttles of the removable spindle type, and to this end the invention consists in the shuttle hereinafter described and particularly defined in the claims.

20 In the accompanying drawings illustrating the preferred form of the invention, Fig. 1 is a plan view of a part of a shuttle embodying the invention; Fig. 2 is a sectional elevation of the same; and Fig. 3 is 25 a transverse section on the line 3—3, Fig. 2.

The illustrated embodiment of the invention is described as follows: The shuttle 10 is provided with the usual bobbin recess 11 to receive the bobbin 12. The bobbin is 30 carried by the spindle blade 13 which is received in the opening in the bobbin. The spindle pintle 14 is received in the spindle block 15 and firmly held in place therein. The spindle blade is provided on its end 35 with a head 16 which engages the tip of the bobbin and holds the latter on the spindle. The spindle pintle is rectangular in cross-section, as shown in dotted lines in Fig. 3. The pintle is received in a correspondingly 40 shaped slot 17 in the spindle block 15. The spindle pintle is provided with lateral bosses 18 which are received in recesses 19 cut in the side walls of the slot 17. The bosses engage the end walls of the recesses 19 and 45 hold the spindle from longitudinal movement in the spindle block. The spindle block is provided with an offset ear 20 which is provided with a bolt hole to receive the bolt 21 by which the ear is bolted to the 50 shuttle, as shown in Fig. 2. The spindle block 15 is also provided with a second bolt hole which receives the bolt 22 which, together with the bolt 21, forms the means for securing the block in the shuttle body. A 55 spring clip 23 is provided which has two

arms that project upwardly and embrace the spindle pintle for the purpose of holding it in position in the spindle block. The arms of the clip are turned toward each other near their ends, and then outwardly from each other at their ends, so as to form a wedge-shaped opening into which the pintle of the spindle may be pressed and which, when the spindle has been pushed down into place, embrace and hold the spindle, as shown in 60 Fig. 3. The spring clip 23 consists of a single piece of wire, the ends of which form the ends of the clip portion proper, and the doubled portion extends horizontally under the spindle block and around the bolt 22, by which the clip is securely held in place 65 with respect to the spindle block. The end of the slot 17 extends through to the end of the block 15, so that the end of the spindle pintle may be received in the hole in the spindle block. The spindle pintle not only extends into but through the hole in the spindle block, and there engages a spring 24 which is a right angle affair, the short end 70 of which extends up over the hole in the end of the spindle block, and the longer portion of which extends under the spindle block, and is provided with a hole which receives the bolt 22. 75

In operation the spindle is removed from the shuttle by lifting it up, thereby disengaging the spindle pintle from the clip and freeing the spindle from the block. The exhausted bobbin is then taken off and the full bobbin put on over the pintle end of the spindle. Then the end of the spindle pintle is thrust into the hole beyond the recess in the spindle block, and the spindle is turned about its end so as to swing the bosses 18 down into the recesses 19 in the spindle block. At the same time the spindle is pressed in between the arms of the clip. The hole which receives the end of the spindle pintle prevents overthrow of the spindle when it is moved downwardly, and the spring 24 affords a resilient means which presses against the spindle firmly to hold it in position. It is to be noted that the end of the pintle is cut so that it is slightly inclined. This conveniences the insertion of a 90 spindle in the spindle block. By cutting 95

off the upper corner of the spindle end the lower corner of the bosses will start into the recesses 19 without endwise pressure being exerted on the spindle. Then as the spindle is forced downward into a horizontal position, the bosses wedge against the edges of the recesses 19 and force the spindle pindle under toward the spring so that it is firmly held in position once it is in place.

10 Having thus described the invention, what is claimed is:

1. A shuttle comprising a body provided with a bobbin recess, a spindle block having a longitudinal body and provided with a longitudinal pindle recess, a spindle having a pindle adapted to be received in the pindle recess of the block, the pindle and block having co-operating projections and recesses to prevent more than slight longitudinal movement of the pindle with relation to the block, a spring clip having arms located at the bobbin end of the block adapted to embrace the spindle and to hold it in position in the block, a spring having a portion yieldingly pressed against the other end of the pindle recess in the block to engage the end of the spindle, the block being provided with an offset ear, a bolt for bolting the offset ear to the shuttle body, and a bolt for bolting the main part of the spindle block, the spring clip and the spring to the shuttle body.

2. A shuttle comprising a body, a spindle block provided with a longitudinal recess, a spring clip at the bobbin end of the block and a spring at the other end of the block, and a bolt for bolting the body of the block, the spring clip and the spring to the shuttle body.

40 3. A shuttle comprising a shuttle body, a spindle block provided with a longitudinal recess secured in the body, a spring clip having spring jaws at the bobbin end of the recess, a spring having a portion located 45 at the other end of the recess, said block being provided with an offset ear, a bolt for bolting the offset ear to the shuttle body, and a part for bolting the body of the block, the spring clip and spring to the shuttle 50 body.

4. A shuttle comprising a shuttle body, a spindle block provided with a longitudinal pindle recess and an offset ear, the recess being rectangular in cross-section, a spindle having a spindle pindle rectangular in cross-section, adapted to be received in the pindle recess of the spindle block, the block and pindle having cooperating projections and recesses to restrain longitudinal movement of the spindle, a spring clip having spring jaws at the bobbin end of the pindle recess, a spring having a portion at the other end of the pindle recess, and two bolts, one for bolting the ear of the block to the shuttle body, and the other for bolting the body of the block, the spring clip and the spring to the shuttle body.

5. A shuttle comprising a body provided with a bobbin recess, a spindle block having a longitudinal body and provided with a longitudinal pindle recess rectangular in cross-section, a spindle having a pindle rectangular in cross-section adapted to be received in the pindle recess of the block, a spring clip having spring arms located at the bobbin end of the block, a spring normally closing the opposite end of the pindle recess and adapted to bear yieldingly upon the end of the pindle, and means for holding the block, clip and spring in place in the shuttle body.

6. A shuttle comprising a body provided with a bobbin recess, a spindle block having a longitudinal body and provided with a longitudinal pindle recess rectangular in cross-section, a spindle having a pindle rectangular in cross-section adapted to be received in the pindle recess of the block, a spring clip having spring arms located at the bobbin end of the block, a spring normally closing the opposite end of the pindle recess and adapted to bear yieldingly upon the end of the pindle, and means for holding the block, clip and spring in place in the shuttle body, said pindle and block having co-operating parts to restrain longitudinal movements of the spindle in the block.

In testimony whereof I have signed my name to this specification.

OVILA J. BENOIT.
